UNITED STATES PATENT OFFICE.

FRANK E. STARR, OF DAYTON, OHIO, ASSIGNOR TO DELCO-LIGHT COMPANY, OF DAYTON, OHIO, A CORPORATION OF DELAWARE.

ENGINE.

Application filed January 24, 1924. Serial No. 688,323.

This invention relates to internal combustion engines, and one of the chief objects of the invention is to simplify the construction by reducing the number of parts and the number of operations necessary to assemble the engine.

In order to accomplish this object one form of the invention provides a structure which may be assembled together as a unit before it is attached to the engine frame. This structure includes a cam shaft adapted to be driven by the engine, valve operating cams and ignition timer and a fuel pump all driven by the cam shaft. These parts are all supported by a cam shaft bearing which is received by the engine frame and secured thereto, the frame and bearing being adapted so that the entire unit may be removed from the engine without disassembling other parts thereof. This unitary structure includes also an electric throttle governor which may be readily attached to the operating arm of a throttle valve adjacent the engine intake.

Further objects and advantages of the present invention will be apparent from the following description, reference being had to the accompanying drawings wherein a preferred form of the present invention is clearly shown.

In the drawings:

Fig. 1 is a view partly in elevation and partly in section of an engine provided in the present invention.

Fig. 2 is a perspective view of an engine valve cam shaft-timer-governor-pump unit embodying the present invention.

Fig. 3 is a longitudinal sectional view thereof.

Fig. 4 is a view of one of the gears shown in Fig. 3.

Fig. 5 is a view of the timer taken on the line 5—5 of Fig. 3.

Fig. 6 is a plan view of the fuel pump.

Figs. 7 and 8 are fragmentary sectional views taken on the lines 7—7 and 8—8 respectively of Fig. 6.

Fig. 9 is a longitudinal sectional view of the electric throttle governor.

Engine cam shaft-timer-pump-governor unit.

In the drawings 20 designates an internal

combustion engine including a crank case 21 mounted on a base 22. The crank case 21 supports an engine cylinder 23 cooperating with a piston 24 which is connected by a rod 25 with a crank 26 which rotates about crank shaft 27. Shaft 27 drives gears 28 and 29 for splash lubricating the moving parts located within the case 21. The engine includes valves operated by mechanism of the overhead rocker arm type, not shown, these rocker arms being operated by push rods 30 and 31 shown in Fig. 1.

The engine intake 32 is connected with a carburetor 33 having a butterfly throttle valve mounted on a spindle 34 which is operated by an arm 35.

Numeral 40 designates in its entirety a unit 70 which is driven by the engine for operating the push rods 31 and 30 for timing the engine ignition, for pumping fuel from a tank to carburetor 33 and for controlling the engine throttle. The unit 40 comprises a frame 75 or shank 41 which is adapted to be received by an aperture 42 in the crank case 21 and is held in position by a set screw 43. Frame 41 provides a bearing for an engine driven shaft 44 which carries a cam 45 for operating the push rod 31, a gear 46 driven by a gear 47 connected with crank shank 27, a cam 48 for operating the push rod 30, and a shoulder 49 which abuts one end of the frame 41. It will be noted that the greatest radii of cams 45 and 48, and the radius of gear 46 are less than the radius of the aperture 42 so that the frame or shank 41 may be withdrawn from the engine after the set screw 43 is removed and the push rod 80 30 is lifted so as to provide clearance for the gear 46.

Endwise movement of the shaft 44 is prevented by the shoulder 49 and by a washer 50 and a nut 51 threaded on shaft 44. The nut is split on one side at 52 and receives a clamping screw 53, so that by tightening the screw 53 nut 51 can be secured in adjusted position.

The frame or shank 41 merges into a cup-shaped timer housing 60 having an end wall 61 to which is attached a plate 62 by means of screws 63 which also secures said plate to a terminal bracket 64 insulated by non-conducting plates 65 and 66. Plate 64 includes an arm 67 carrying a contact 68 which

cooperates with the contact 69 carried by a breaker lever 70 which is pivoted at 71. The lever 70 includes a rubbing block 72 cooperating with a cam 73 which is provided by flattening a portion of the shaft 44 as shown at 74 in Fig. 5. A leaf spring 75 having one end connected with an insulated terminal 76 and intermediate portion bent around the pivot 71 and the other end connected with the pin 77 on the breaker 70 serves to conduct current between the contact 69 and the terminal 76 and also to maintain the contacts in engagement or the rubbing block 72 in engagement with the cam 73. The plate 64 carries a terminal 78. The ignition coil and current source are connected to the timer by means of wires 79 and 80 which are attached to terminals 78 and 76 respectively.

20 The apparatus for governing the engine throttle includes a bracket 81 having an apertured disc portion 82 which is attached by screws 83 to ears 84 provided by the housing 60. The bracket 81 provides a platform 85 having an aperture 86 and an annular flange 87 (see Fig. 9). The flange 87 supports a non-conducting washer 88 upon which is mounted an electro-magnetic winding 89 having terminals 90 and 91 which extend through the aperture 86. The winding 89 surrounds a non-magnetizable tube 92 within which slides a magnetizable plunger 93 attached to a rod 94 which is connected with the throttle valve shaft 35 (see Fig. 1). 30 The plunger 93 is maintained in position shown in Fig. 9 by means of a spring 95 located between a washer 96 which rests on the tube 92, and a collar 97 adjustably secured to the rod 94 by set screws 98. The 40 coil 89 is enclosed by a case 99 having a cover 100 which is apertured to receive and support a tube 92. The case 99 is attached to the flange 87 by screws 101.

The engine driven fuel pump is of the 45 diaphragm type described and claimed in detail in the copending application of Charles L. Lee and Charles F. Kettering, fuel supply systems, Serial No. 633,511, filed April 20, 1923.

50 Briefly, this pump includes frame members 110 and 111 which are attached by screws 112. These members are so constructed that when they are connected to the bracket 81 by the screws 113 a cover will be provided for the opening 114 in the bracket 81. Therefore, it is apparent from Fig. 3, that the parts 60, 82, 110 and 111 cooperate to provide a housing for the ignition timer and for the pump operating mechanism.

55 The pump operating mechanism includes a one tooth annular worm gear 115 which is operatively connected with a reduced portion 116 of shaft 44 and is held in position 60 by nut 117 cooperating with a threaded end

of said shaft. The worm gear 115 drives a gear 118 which is attached to a hub 119 carrying a self lubricating sleeve 120. Hub 119 is journaled within a self lubricating sleeve 121 attached to a sleeve 122 which is supported by a plate 123.

Gear 118 carries a cam 125 which engages a roller 126 mounted on a shaft 127 carried by an arm 128 attached to a pump rod 129 by means of a pin 130. The shaft 127 carries a roller 131 adapted to cooperate with guides 132 provided by the frame 110 in order to prevent rotation of the pump rod 129. The cam 125 is adapted to push the rod 129 downwardly twice during every revolution of the gear 118. The roller 126 is normally held in engagement with the cam 125 by means of a spring 133 bearing at one end against the plate 123 and pressing upwardly against a plate 134 which is attached to the pump rod 129. A flexible bellows 135 is attached at its upper end to a plate 134 and its lower end to the plate 123. The plate 123 is attached to the pump housing 111 by screws 136 there being a packing member 90 between the plate 123 and the housing 111. Obviously the spring 133 holds the gear 118 and the hub 119 against the lower ends of sleeve 121 and sleeve 122. To render the pump inoperative or hand operative there 95 is provided (see Fig. 2) an arm 140 which is connected with a shaft 141 journaled in pump frame 110 and connected with an arm 142 which presses upon a lug 143 provided 100 on the arm 128. If the finger 142 is rotated counterclockwise the rod 129 will be pushed downwardly so that the cam 125 will not engage the roller 126. Downward movement of the gear 118 is limited by a shelf 118^a for engaging the lower side of the gear 105 118. The pump rod 129 slides up and down in the rotatable bearing sleeve 120 and its lower end is guided by a self lubricating bearing sleeve 144 supported within a recess 145 of the lower portion of the frame 110 110.

The space between the bellows 135 and the pump housing 111 provides a chamber 150 for receiving fuel. Passage of fuel through this chamber is controlled by valve 115 mechanism which will now be described. The downward movement of the bellows 135 causes fuel to be sucked through the opening 151 (see Fig. 8) through a screen 152 and passages 153 and 154, past a valve 155 resting on a seat 156, through a recess 157 in valve guide plate 158, and then through an aperture 159 connecting the recess 157 with the chamber 150. During the down stroke of the pump rod 129 the valve 160 shown in Fig. 7 remains on its seat 161. On the up stroke of the pump rod 129 the valve 155 remains on a seat 156 due to the back pressure of the fuel and a valve 160 opens to 120 allow the passage of fuel through an open- 125 130

ing 162 in the top wall of housing 111, past a valve 160, through a recess 163 provided by the valve cover 158, and then out of the pump through the passages 164 and 165. 5 The valve cover 158 is secured to a housing 111 by screw 166 and the packing gasket 167 is provided. The cover 158 provides a cover for the screen chamber 168 and is provided with spaced lugs 169 for guiding the 10 valves 155 and 160.

The pump inlet 151 is connected by a pipe 170 with the fuel tank 171 and the pump outlet 165 is connected by pipe 172 with the carburetor 33 which contains a constant 15 level fuel reservoir connected with an overflow 173 leading back to the fuel tank 171.

The operation of the engine causes the gear 28 to drive the shaft 44 through the gear 46. Rotation of the shaft 44 will 20 cause the cams 45 and 48 to operate the valve mechanism in correct timing with the engine shaft and the breaker lever 70 will be operated to break the ignition primary circuit at the desired instant. The gear 25 115 will be rotated to thread its way through the notches in the gear 118 to produce the rotation of the cam 125 and the reciprocation of the pump rod 129. The operation 30 of the fuel pump is therefore responsive to the speed of the engine and is of sufficient capacity to supply the carburetor with the maximum requirement of fuel.

The throttle governor spring 95 normally holds the throttle valve in a predetermined position to limit the speed of the engine. The magnet coil 89 is included in an electrical circuit which is responsive to a demand for current. Therefore, the ampere turns of coil 89 increases with the current demands and will open the throttle valve in order that the engine may develop the power required for driving the generator under these conditions. An electrical system in which the governor may be used is shown in my copending application, Serial No. 689,602, filed January 31, 1924.

While the form of embodiment of the invention as herein disclosed, constitutes a preferred form, it is to be understood that other forms might be adopted, all coming 50 within the scope of the claims which follow.

What is claimed is as follows:

1. An internal combustion engine comprising, in combination, a frame; an engine driven shaft projecting through said frame; an ignition timer having a housing extending through the frame and providing a bearing for said shaft, and means covering the 55 housing and including a pump operated by said shaft.

2. A device of the character described comprising in combination a casing having a shank portion provided with a concentric cup portion; a shaft journaled in said shank

portion and extending into the cup portion; an ignition device in the cup portion and operatively connected with the shaft; a pump; a controller; and a member adapted to be secured to the cup and including means 70 for mounting the pump in operative relation with the shaft, said member including a bracket extension providing a mounting platform for the controller.

3. A structure comprising a shank portion 75 adapted to be received by an engine frame and a cup portion concentric with the shank, a shaft extending through the shank into the cup portion, a pump having a frame detachably secured to the cup portion and providing a cover for said cup portion, and means connecting the pump operating mechanism and the shaft, said means being automatically disconnected by the removal of the pump from the cup portion. 80

4. An internal combustion engine comprising, in combination, a crank case provided with an aperture; a crank shaft journaled in the crank case; and a structure removable as a unit and received by the aperture, said structure including a valve cam shaft driven by the crank shaft, ignition timer mechanism, pump mechanism, driving connections between the cam shaft and said mechanisms, said connections being constructed and arranged whereby one of said mechanisms may be removed while the other mechanism is maintained in operative relation. 85

5. An internal combustion engine comprising, in combination, a crank case provided with an aperture; a crank shaft journaled in the crank case; and a structure removable as a unit and including a member received by the aperture, a valve cam shaft 100 journaled within the member, ignition timer mechanism including rotatable means carried by the shaft and a relatively stationary means carried by said member, pump mechanism, driving connections between the cam 105 shaft and pump mechanism, said connection being constructed and arranged whereby said pump mechanism may be removed while the rotatable and relatively stationary means of said timer mechanism are maintained in cooperative relation with the cam shaft. 115

6. An internal combustion engine comprising, in combination, a fuel intake having a throttle; a governor for said throttle; a crank case provided with an aperture; a crank shaft journaled in the crank case; and a structure removable as a unit and received by the aperture, said structure including a valve cam shaft driven by the crank shaft, ignition timer mechanism, pump mechanism, driving connections between the cam shaft and said mechanisms, a support for said throttle governor inclosing a portion of said connections, said connections being con- 120 125

- 4
- structed and arranged whereby one of said mechanisms may be removed while the other mechanism is maintained in operative relation.
- 5 7. An internal combustion engine comprising, in combination, a crank case provided with an aperture; a crank shaft journaled in said crank case; and a structure removable as a unit including a housing received 10 by said aperture, a second shaft journaled in said housing and extending through said aperture and arranged to be driven by the crank shaft, a second housing carried by the first housing, ignition timer mechanism with- 15 in one of said housings, pump mechanism within the other housing, and driving connections between the second shaft and said timer and pump mechanisms, said driving connections being constructed and arranged 20 whereby the mechanism in said second housing may be disengaged from said shaft while the mechanism in the first housing is maintained in operative relation with the shaft when said second housing is removed.
- 25 8. An internal combustion engine comprising, in combination, a crank case provided with an aperture; a crank shaft journaled in said crank case; and a unitary structure including a housing received by 30 said aperture and having an opening in one wall thereof, a second shaft journaled in said housing and extending through said aperture and arranged to be driven by the crank shaft, a second housing carried by the first housing and having an 35 opening in one wall thereof and registering with the opening in the first housing, an ignition timer mechanism within one of said housings, a pump mechanism within 40 the other of said housings, driving connections between said second shaft and said mechanism within the first housing, and driving connection between said second shaft and said mechanism within the second housing, 45 said last connection extending through the openings and detachable adjacent said opening whereby the mechanism in said second housing may be disengaged from the shaft to provide access to the mechanism in said 50 first housing when said second housing is removed.
9. An internal combustion engine comprising, in combination, a fuel intake having a throttle; an electrical governor 55 for the throttle; a crank case provided with an aperture; a crank shaft journaled in said crank case; and a structure removable as a unit including a housing received by said aperture, a second shaft 60 journaled in said housing and extending within the crank case and arranged to be driven by the crank shaft, a second housing, ignition timer mechanism within one of said 65 housings, pump mechanism within the other housing, a support for said governor inter- 70 posed between said housings, and driving connections between the second shaft and said mechanisms, said second housing and said support being apertured to receive and inclose said driving connections, said driving connections being constructed and arranged whereby the mechanism in said second housing may be disengaged from said shaft while the mechanism in the first housing is maintained in operative relation with the shaft when said second housing is removed. 75
10. An internal combustion engine comprising, in combination, a fuel intake having a throttle; a governor for said throttle; a crank case provided with an aperture; a crank shaft journaled in the crank case; and a structure removable as a unit, a housing received by said aperture, a valve cam shaft journaled in said housing and driven by the crank shaft, a second housing carried by the first housing, ignition timer mechanism within one of said housings, pump mechanism within the other housing, a support for the throttle governor interposed between the housings, and driving connections between the cam shaft and said mechanisms, said driving connection being inclosed by the housings and said support, and having a joint within the support whereby the mechanism in the second housing is disengaged from the cam shaft at said joint when the second housing is removed while the mechanism in the first housing is maintained in operative relation with said cam shaft. 80 85 90 95 100
11. An internal combustion engine comprising, in combination, a frame, an engine driven shaft; and a structure removable as a unit including ignition timer mechanism having rotating and stationary portions, 105 pump mechanism, a housing for said timer mechanism carried by the frame, said housing having an opening providing access to the rotating and stationary portions of the timer mechanism, a second housing for the 110 other mechanism carried by the first housing and covering said opening, driving connections between the shaft and the mechanisms, said connections extending into the first housing and through said opening, said 115 driving connections being constructed and arranged whereby the pump mechanism is disconnected while the timer mechanism is maintained in operative relation when the second housing is removed. 120
12. An internal combustion engine comprising, in combination, a fuel intake having a throttle; an electrical governor for the throttle; a frame; an engine driven shaft; and a structure removable as a unit including ignition timer mechanism, pump mechanism, a housing for one of said mechanisms carried by the frame, said housing having an opening, a second housing for the other mechanism, a support for said governor in- 125 130

terposed between said housings and having structured and arranged whereby the pump an opening extending therethrough, driving mechanism is disconnected while the timer connections between said shaft and mechanism is maintained in operative relation when the second housing is removed. 10
nisms, said connections extending through the openings in the first housing and sup- In testimony whereof I hereto affix my port, and inclosed by said housings and sup- signature.

FRANK F. STARR.
